UNITED STATES PATENT OFFICE.

SIGMUND STERNAU, OF NEW YORK, N. Y.

DESIGN FOR A KETTLE.

SPECIFICATION forming part of Design No. 23,762, dated November 6, 1894.

Application filed October 6, 1894. Serial No. 526,173. Term of patent 3½ years.

To all whom it may concern:

Be it known that I, SIGMUND STERNAU, a citizen of the United States, residing in New York, county of New York, and State of New York, have invented and produced a new and original Design for Kettles, of which the following is a specification, reference being had to the accompanying drawing, which shows the kettle in perspective.

10 The leading or characteristic feature of my design is the kettle body, shaped and ornamented as shown, and having projecting upwardly therefrom a fanciful handle.

A is the kettle body, having the contour or shape shown, resting on the base a and ornamented as at a'.

B is the spout ornamented at b, and C the handle of fanciful design extending upwardly from the body A.

What I claim is—

20 The design for a kettle as hereinabove shown and described.

SIGMUND STERNAU.
